STRICKLAND L. KNEASS, OF PHILADELPHIA, PENNSYLVANIA, ASSIGNOR TO WILLIAM SELLERS & COMPANY, INCORPORATED, OF PHILADELPHIA, PENNSYLVANIA, A CORPORATION OF PENNSYLVANIA.

STARTING-VALVE MECHANISM.

1,300,280.

Specification of Letters Patent. Patented Apr. 15, 1919.

Application filed May 22, 1917. Serial No. 170,152.

To all whom it may concern:

Be it known that I, STRICKLAND L. KNEASS, a citizen of the United States, residing at Philadelphia, county of Philadelphia, and 5 State of Pennsylvania, have invented a new and useful Improvement in Starting-Valve Mechanism, of which the following is a full, clear, and exact description, reference being had to the accompanying drawings, which 10 form a part of this specification.

It is an object of my invention to provide a safe operating partly balanced valve, which cannot be opened by jarring and vibration when under pressure, and it is a 15 further object to provide means whereby the opening of the valve and the amount of flow of fluid through its port can be regulated.

It is applicable chiefly to the operation of the non-lifting form of steam injector upon 20 locomotives, rendering the starting and stopping of the feed especially convenient, besides permitting a regulation of the flow 25 of steam, permitting a higher economy and efficiency in its operation, reducing at the will of the operator the weight of the steam used in proportion to the amount of feed to the boiler.

My invention also permits admission of a 30 very small amount of steam when it is desired to use the injector as a heater for the water in the tender supply tank, and this is done without the use of supplemental external valves or without danger of wear or abrasion of the faces or seats of the operating valve.

My invention also includes the use of two 40 or more loosely guided check valves in the same axial line with seats normal to their axes, the face of each valve being of the same external and internal dimensions as the seat upon which it rests, so that the clearance between the guides for the valve and the valves themselves permit a small amount of lateral change of position, causing a self- 45 grinding action between valve seats and the valve faces which tends to retain their normal steam tight condition and materially increases the durability and effectiveness of the device.

50 My invention also includes operating means, consisting of a hand lever, link and attachments which may be rotated upon a vertical axis to any position desired by the

operator, and then locked in position; this 55 enables the extended part of the valve casing to be placed close to a locomotive boiler and in the transverse plane of the conducting steam pipe, and the operating lever and means, so placed as to minimize the amount 60 of space required in the locomotive cab.

The figure illustrated shows the invention 65 partly in sectional elevation.

The inlet passage *b* and the discharge passage *c* of the casing *a* are separated by a 70 septum or partition *a'* which is provided with the port *d* permitting communication between the passages. The inlet and discharge passages are provided with the ports *e* and *f* respectively, for connection with a steam line.

Adjacent to the port *d* is the valve seat *g* upon which the main valve *h* is adapted to 75 seat. The main valve *h* is bored centrally and provided on its top with the valve seat *i*, upon which is adapted to seat the head *j* of the secondary valve. The valve *h* is provided with wings *k* affording ports permitting communication between the central bore of the main valve and the discharge 80 passage. The secondary valve *j* is provided with the upwardly extending stem *m* adapted, when the valve is raised, to act as a stop on contacting with the valve cap *n*.

Below the head *j* of the secondary valve, the body *o* of the secondary valve fits loosely 85 within the central bore of the main valve *h*. The body *o*, except for a short distance immediately below the head *j*, is cut away to permit communication from the central bore to the discharge passage between the wings *k*. 90 The main valve is counterbored at *l* for a short distance below its upper end, the width of the solid part of the valve body *o* being slightly greater than the depth of the counterbore.

The lifting stem *p* extends through the stuffing box *q* in the lower part of the casing and upward, through the discharge passage, into the central bore of the main valve *h* to contact with the lower end of the secondary 100 valve. The part of the stem *p* which extends into the bore in the main valve is reduced to be a loose fit therein and affording a shoulder *r*, so that when the stem *p* is lifted beyond the distance required to fully open the 105 secondary valve the shoulder will contact

with the main valve and raise it from its seat. To the lower end of the stem p is pivoted one end of the link s , the other end being pivoted to the arm t of the bell crank 5 lever u . The lever u is pivoted to the bracket v which, in turn, is attached to an extension of the casing by means of the ring w , and is rotatable about the axis of the annular bearing 5 onto which the ring is fitted and is 10 locked in radial position by the nut x . The bracket v also carries the notched quadrant y , the notches of which are adapted to be engaged by the pawl z carried by the lever. The pawl is maintained in locking position 15 by the rod 2 and spring 3; and is released by pressure on the button 4.

The operation is as follows:

Steam enters at e and filling passage b exerts downward pressure upon the upper face 20 of the main valve and the secondary valve, holding them firmly to their seats, so that there shall be no flow through the discharge passage c . When the operating lever u is pulled downward, the arm t and link s cause 25 an upward movement of the stem p , causing it to exert a lifting action upon the winged extension o of the secondary valve. When the secondary valve is lifted, steam flows through the central opening of the main 30 valve h into the discharge passage c and through the connecting pipes to the injector or other operated device. The fluid pressure within this passage and connecting pipes gradually rises in proportion to the effective areas of the opening controlled by 35 the secondary valve and the terminal discharge opening. This accumulation of pressure beneath the main valve partly balances the pressure of the fluid upon the upper face 40 of the main valve, and permits it to be opened without undue effort when the lever u is pulled outward, for the further upward movement of the lifting stem p gives contact between its enlarged diameter and the cylindrical guide of the winged extension of 45 the main valve h , lifting the main valve from its seat, permitting full or required flow of steam through the port of the valve.

When the secondary valve or main valve, 50 or both, are lifted, the pressure of the fluid exerts pressure upon the lifting stem p to force it outwardly from the valve casing and return the valves and operating lever to their closed positions. This action is 55 prevented and the several valves retained in their desired positions by means of the pawl z , which automatically locks into the notched quadrant y . It will be observed that a series of notches is provided so that the valves may 60 be retained in any intermediate point between their open and closed positions.

It is frequently desirable that a small amount of steam be permitted to flow through an operating valve, for example, to 65 heat the feed water supply. For this pur-

pose, the lever u is pulled (say) one notch, slightly opening the secondary valve j , admitting steam, which passes between the central bore of the valve h and the loose fitting body of the secondary valve, and the ports 70 between the wings k of the valve h into the discharge passage. The solid part of the valve body o below its head j disposes the throttling area away from the contact face of the secondary valve and its seat and prevents wear or abrasion of these surfaces, due to the rapid flow of the steam from the high to the low pressure areas.

Having now fully described my invention, what I desire to claim and protect by Letters Patent is:—

1. Valve mechanism comprising a valve casing having inlet and outlet passages, a septum separating said passages and provided with a port, a main valve seated on 85 the septum, a secondary valve of lesser area seated upon the main valve, the main valve having a bore and a counterbore and the secondary valve having a head and a solid cylindrical extension, the latter being of 90 greater length than said counterbore, whereby, when the secondary valve is partly opened to afford a restricted passage for steam between its cylindrical extension and the main valve bore, attrition of both the 95 face of and seat for the secondary valve will be prevented.

2. Starting valve mechanism comprising a valve casing having inlet and outlet passages, a septum separating said passages 10 and provided with a port, a main valve seated on the septum, a secondary valve of lesser area seated upon the main valve, each valve adapted to be returned to its seat after being opened and to be held thereon by fluid 10 pressure, the main valve having a central bore and the secondary valve having a body loosely fitting the bore and a head of larger diameter the lower face of which is adapted when the secondary valve is closed to seat 11 upon the upper face of the main valve surrounding its bore, the body of the secondary valve being solid for a relatively short distance from its head and thence cut away and the central bore of the main valve being 110 counterbored from its upper end for a distance somewhat less than the length of the solid part of the body of the secondary valve.

3. Starting valve mechanism comprising a valve casing provided with inlet and outlet passages, a main valve and a secondary valve held to their respective seats by fluid pressure, said secondary valve being movable to positions to allow either a relatively restricted or a relatively free passage of steam, 120 a lifting stem in the discharge passage, an operating lever adapted to lift said stem to lift the secondary valve successively into its throttling position and its more fully open position and then lift the primary valve 125 130

from its seat, and means to hold said stem and its actuating lever in partially and fully advanced positions.

4. Starting valve mechanism comprising
5 a valve casing having inlet and outlet pas-
sages, two check valves opening independ-
ently and held to their respective seats by
fluid pressure, one of said valves having a
bore, a lifting stem in the discharge passage,
10 and means to raise said lifting stem to suc-
cessively operate said valves, said lifting
stem extending into, and having a loose fit
in, said bore to allow free and unrestricted
seating and alinement of the valves.
- 15 5. Starting valve mechanism comprising
a valve casing having inlet and outlet pas-

sages, a main valve having a bore and a sec-
ondary valve operating independently and
held to their respective seats by fluid pres-
sure, a lifting stem in the discharge passage,
20 and means to raise said lifting stem to suc-
cessively operate the secondary valve and
the main valve, said lifting stem extending
into, and having a loose fit in, the bore of
25 the main valve, and the body of the second-
ary valve fitting loosely within the bore of
the main valve.

In testimony of which invention, I have
hereunto set my hand, at Philadelphia, on
this 19th day of May, 1917.

STRICKLAND L. KNEASS.
